UNITED STATES PATENT OFFICE.

CHARLES TAYLOR, OF NOGALES, ARIZONA.

DEVICE FOR THE AERATION AND EMULSIFYING OF PULP FOR FLOTATION.

1,299,059.

Specification of Letters Patent.

Patented Apr. 1, 1919.

Application filed November 8, 1917. Serial No. 200,890.

To all whom it may concern:

Be it known that I, CHARLES TAYLOR, a citizen of the United States, residing at Nogales, in the county of Santa Cruz and State of Arizona, have invented new and useful Improvements in Devices for the Aeration and Emulsifying of Pulp for Flotation, of which the following is a specification.

10 This invention relates to a device for the aeration and emulsifying of pulp for flotation.

An object of the present invention is to provide a simple, compact, easily operated and cheaply manufactured, efficient device for the aeration and emulsifying of pulp for flotation and particularly a form of apparatus which will eliminate the use of power driven emulsifiers, agitators, air pumps, and the like. Further objects will hereinafter appear.

The invention consists of the parts and the construction and combination of parts as hereinafter more fully described and claimed, having reference to the accompanying drawings, in which—

Figure 1 is a side elevation, partly in section, showing the form of apparatus employed.

30 Fig. 2 is a front view partly broken away and partly in section.

Fig. 3 shows a modified form of the distributor.

Fig. 4 is a detail view showing means for adjusting the baffle plates.

Referring to the drawings in detail; A indicates a hopper or other suitable receptacle, to which the pulp to be treated is delivered by a penstock 2. This penstock 40 may be directly connected with a tube or other mill, or pulp from a mill may be delivered directly to the hopper by a sand pump or other suitable form of elevator. Connected with the bottom of the hopper 45 is a pipe 3, which is preferably square in cross section. This pipe is provided with a plurality of openings 4 into which are inserted upwardly extending inclined tubes 5. These tubes are provided for the purpose 50 of permitting an ingress of air as the pulp descends through the pipe; that is, the falling of the pulp through the pipe 3 creates a sufficient vacuum to draw air through the tubes 5 and thereby form a perfect mixture 55 of air and pulp.

The pipe thus provided not only serves

as a means for aerating the pulp but it also serves as an emulsifier, thereby eliminating the use of power driven agitators, emulsifiers, air pumps, and the like, and at the same time provides a structure which is simple and compact in construction and can be quickly erected and cheaply installed in a minimum of space in any plant. The oil or acid is added to the pulp while it is ground or it may be delivered directly to the hopper or may be admitted through one of the tubes 5, and as a perfect emulsification and aeration takes place, it can readily be seen that the oil or other agent admitted will be thoroughly mixed before the pulp enters the Spitzkasten where the froth is separated from the pulp and tailings.

While the pipe 3 may deliver the pulp directly to the Spitzkasten, I prefer to interpose a combination distributor and agitator constructed substantially as shown in Figs. 1 and 2. This distributor consists of a triangular-shaped member including a pair of side walls 6 and 7, between which are suitably secured a number of staggered baffle plates 8, the distributor being so proportioned and arranged that no resistance whatever is impressed upon the pipe 3 through which the pulp flows. The side walls of the distributor preferably taper from the lower end to the top, being wider at the top than at the bottom and the mouth of the distributor is preferably positioned an inch, more or less, below the surface level or overflow line in the Spitzkasten.

While the distributor is here shown as being triangular shape in front view, it is obvious that any other suitable form of distributor may be employed. The only feature of importance to be considered in connection with the distributor is that it has a capacity sufficiently large to prevent any resistance to the discharge of pulp through the pipe 3.

Any form of Spitzkasten may be employed for the separation of the froth and tailings, a valve 8' being provided to regulate the discharge of the tailings and the overflow of the froth. Where composite ores are handled it is obvious that the pulp may be run over or re-treated as often as necessary, the present apparatus being of considerable advantage in that case as the simplicity of the construction and arrangement permits re-treatment of the pulp to be readily taken care of. A baffle, such as

shown at 9, may be employed if desired, but it does not form any important feature of the present arrangement.

5 While the pipe 3 has here been shown as constructed of planks which are assembled to produce a pipe square in cross section, it is obvious that it may be constructed of metal or any other material desired. I also wish it understood that various changes in 10 form, proportions and minor details of construction may be resorted to within the scope of the appended claims and that I do not wish to limit myself to the specific design and construction here shown.

15 By referring to Fig. 3 it will be seen that the baffles or distributing plates employed are secured alternately, one to each side wall of the distributing box. This is of importance as when they are fastened together in this manner they will interlock or break the joints, each strip with relation to its fellow strip on the opposite side. Another feature shown in the modification is that each strip is so secured, as shown at 20 25 30 35 40 45 50 55 60 65 70 75 80 85 90 95 100 105 110 115 120 125 130 135 140 145 150 155 160 165 170 175 35 Having thus described my invention, what I claim and desire to secure by Letters Patent is—

1. An aerator and emulsifier for flotation concentration comprising a pipe 40 through which the pulp to be treated is adapted to pass, and means for admitting air to the pipe at points throughout the length thereof so as to cause mixture of air with the pulp throughout the entire passage 45 of the latter through the pipe.

45 of the latter through the pipe.

2. An aerator and emulsifier for flotation concentration comprising a vertically positioned pipe through which the pulp to be treated is passed, and a plurality of tubes
50 connected with the pipe throughout the length thereof through which air is admitted to aerate the pulp during its passage through the pipe said tubes extending through the pipe sides and having their inner ends substantially flush with the inner
55 face of the pipe.

3. An aerator and emulsifier for flotation concentration comprising a vertically positioned pipe through which the pulp to be treated is passed, and a plurality of upwardly extending, angularly disposed tubes connected with the pipe throughout the length thereof through which air is admitted to aerate the pulp during its passage through the pipe said tubes extending

through the pipe sides and having their inner ends substantially flush with the inner face of the pipe.

4. An aerator and emulsifier for flotation concentration comprising a hopper 70 adapted to receive the pulp to be treated, a vertically positioned pipe connected with the bottom of the hopper, said tube having a plurality of air inlet openings formed therein throughout its length, and a pulp 75 distributing and agitating member connected with the lower end of the tube.

5. An aerator and emulsifier for flotation concentration comprising a hopper adapted to receive the pulp to be treated, 80 a vertically positioned pipe connected with the bottom of the hopper, said pipe having a plurality of air inlet openings formed therein throughout its length, a pulp distributing and agitating member connected 85 with the lower end of the tube, said member comprising a pair of spaced plates, and a plurality of staggered superposed deflecting plates secured between the first named plates. 90

6. An aerator and emulsifier for flotation concentration comprising a hopper adapted to receive the pulp to be treated, a vertically positioned pipe connected with the bottom of the hopper, said pipe having 95 a plurality of air inlet openings formed therein throughout its length, a pulp distributing and agitating member connected with the lower end of the tube, said member comprising a pair of spaced triangular-shaped plates disposed on angles with relation to each other, side members connecting the triangular plates, and a plurality of staggered superposed deflecting plates secured between the triangular plates. 100 105

7. A distributor and agitator for flotation concentration composing a pair of spaced triangular-shaped plates, distributing plates secured to each plate and offset with relation to each other, and means for adjusting the position of each distributing plate. 110

8. A pulp distributing and agitating member comprising a pair of interspaced, triangular-shaped plates disposed on angles with relation to each other, side members connecting the triangular plates, a discharge pipe connected with the upper end of the plates at the apex of the same, a plurality of staggered, superposed deflecting plates secured between the triangular plates, and means for adjusting the position of each deflecting plate. 115 120

9. In an aerator and emulsifier for flotation concentration, a pipe having a discharge, means to admit air to the pipe so as to cause mixture of air with the pulp throughout the passage of the latter through the pipe, and a combined distributor and agitator connected to the discharge of the pipe. 125 130

10. In an aerator and emulsifier for flotation concentration, a pulp conveying pipe, and means to admit air to said pipe by suction created by the pulp moving through
5 the pipe, said means being connected to the pipe so that the interior of the latter offers no obstruction to the free passage of the pulp therethrough.

In testimony whereof I have hereunto set my hand in the presence of two subscribing 10 witnesses.

CHAS. TAYLOR.
